COMBINED FILTER SILENCER AND VALVE BRACKET FOR AN AQUARIUM

Allan H. Willinger, 56 Gail Drive, New Rochelle, N.Y.

Filed Sept. 11, 1961, Ser. No. 66,683

Term of patent 14 years

(Cl. D91—2)

FIGURE 1 is a front perspective view of a combined filter silencer and valve bracket for an aquarium, showing my new design;

FIGURE 2 is a rear perspective view thereof;

FIGURE 3 is an exploded top plan view thereof; and

FIGURE 4 is an exploded side elevation thereof.

I claim:

The ornamental design for a combined filter silencer and valve bracket for an aquarium, substantially as shown.
